CAN SEALING APPARATUS

John Junkunc, Chicago, Ill.

Application April 9, 1936, Serial No. 73,402

7 Claims. (Cl. 113—23)

The present invention relates to a can sealing apparatus and more particularly to a hand-operated apparatus for seaming a cover onto a can in such a manner that the flanges of the cover and the adjacent edge of the can body are rolled together and tightly closed one against the other to make a hermetically sealed joint. The present apparatus is especially useful to a housewife who does her own canning.

10 An object of the present invention is to provide a can sealing apparatus which may be economically manufactured and thus readily saleable at moderate prices.

Another object of the present invention is to 15 provide a can sealing apparatus, of the hand-operated type, which is readily adaptable for sealing cans of different sizes.

Still another object of the present invention is to provide a hand-operated can sealing apparatus 20 wherein the follower plate for holding a can and cover against a driver plate or chuck is axially adjustable to accommodate cans of different sizes, and which plate is also provided with a plurality of configurations differently 25 spaced, radially, to accommodate cans of different diameters for centering the same on the follower.

A still further object of the present invention is to provide means for adapting a can sealing 30 apparatus to be used as a can opening apparatus.

The above, other and further objects of the present invention will be apparent from the following description and accompanying drawings.

The accompanying drawings illustrate an embodiment of the present invention, and the views thereof are as follows:

Figure 1 is a vertical axial sectional view of the apparatus of the present invention, with a can in position for sealing, and with the adjustment for the follower plate extended to accommodate a can of intermediate height, i. e., a No. 2 can, which the present form of the invention is capable of sealing, and showing the follower plate elevated to hold the can and cover in driving 45 relation with the driver or chuck.

Figure 2 is a view, partially in elevation and partially in axial section, of the driving or chuck plate and one manner of connecting the plate to a driving spindle, and showing removable connections between the spindle and plate.

Figure 3 is a view, partially in plan and partially in section, illustrating another manner of removably connecting the driving spindle and chuck in driving relation.

55 Figure 4 is a fragmental view, partially in ele-

vation and partially in section, of one means, such as a pin, for preventing rotative movement of the follower plate during the flanging operation.

Figure 5 is a horizontal sectional view taken substantially in the plane indicated by the line 5 V—V of Figure 1.

Figure 6 is an enlarged axial sectional view, with parts in elevation, through the follower plate of the present invention, its supporting spindle, and a telescopically arranged tail pin, together 10 with one means for adjustably connecting the spindle and tail pin in desired arrangement.

Figure 7 is a plan view of the follower plate showing the illustrated manner of providing a plurality of indentations for affording centering 15 means for cans of different diameters, accommodations being here shown for cans of four different diameters.

Figure 8 is a fragmental sectional view, showing a cover applied to the open flared margin of 20 a can, ready for sealing.

Figure 9 is a view, partially in section and partially in elevation, showing the first seaming operation as carried out by the apparatus of the present invention.

Figure 10 is a view, in vertical section, showing the manner of accomplishing the second seaming operation.

Figure 11 is a view, partially in section and partially in elevation, showing the cutting roller 30 of the present apparatus in position preparatory to removing a cover from a can.

The drawings will now be explained.

A frame, designated generally as A, is provided with means for removably securing it to 35 support B, such as a table, ledge or bench. The illustrated means for accomplishing this purpose include a lug 1, formed as a part of the frame structure and projecting downwardly from the bottom of the frame, which is threaded to receive 40 a thumb bolt 2 having a head 3 suitably connected to the bolt for slight movement, and a wing 4 for manipulating the bolt.

The frame A is constructed with a bottom 5 adapted to rest on top of the ledge or other 45 support B, and having an upper overhanging part 6. The body of the frame is offset vertically to provide a space for receiving a can and certain of the operating parts of the present apparatus. The overhanging part 6 is provided with 50 an upstanding bored boss 7 which serves as a bearing for a driving spindle 8. The upper end of the spindle 8 is apertured to receive an operating hand 9, which is shown in the form of a rod bent at its outer end upwardly to receive 55

a grip 10, which grip is retained in position on the upstanding end of the rod 9 by means of a bolt 11 entering the upper end of the grip 10 and threaded into a threaded bore 12 of the 5 upstanding end of the rod, as may be readily observed in Figure 1. The rod is secured to the spindle 8 by means of a pin 13 or other suitable fastening means.

In the form of coupling shown in Figures 1 and 10 2, the lower or inner end of the spindle 8 has a reduced cylindrical end 14 which has a bore 15 to receive two spring-pressed balls 16 and 17 at the extremities of the bore, which balls are normally forced apart by means of an intervening 15 spring 18 interposed in the bore. Above the bore 15 is another bore 19 which receives a pin 20, the ends of which extend outwardly of the surface of the reduced end portion 14 of the spindle to receive notches formed in an upstanding neck 22 20 of the driver or chuck, designated generally at C.

The driver or chuck plate C is preferably fashioned from pressed metal, for economy of manufacture and light weight, and has its peripheral portion 23 serrated to serve as a driving chuck 25 for an applied can and cover. The driver C is applied to the lower end of the spindle 8 by forcing the neck 22 of the driver over the balls 16 and 17, as shown in Figure 2, with the notches 24 engaging the extremities of the pin 20, thus 30 connecting the spindle and driver in relative non-rotative relationship.

In the modification shown in Figure 3, the inner or lower end of the spindle 8 has its chuck receiving end provided with two oppositely disposed flat surfaces 60 and 61 which cooperate with similarly flattened portions of the neck 22a of a driver or chuck C' to effect driving connection between them. The neck 22a of the chuck C' is held on the spindle by spring-pressed balls, 40 such as balls 16 and 17 heretofore described.

The part 24 of the frame A extends downwardly from the bottom 5 of the frame, and is cylindrically bored at 25, which bore is open at its upper end and has an apertured lower end 45 wall 26. The bore 25 is in axial alignment with the bore in the boss 7 at the upper part of the frame. Slidable within the bore 25 is a spindle 27 having a polygonal bore 28 opening through its lower end and having its upper end reduced in diameter, as at 27a. In the height of the spindle, there are provided a plurality of cross bores 29, 29a, 29b, 29c, and 29d, perpendicular to the axis of the spindle, for receiving a pin 30, for a purpose to be later explained.

55 Rotatably attached to the reduced end 29 of the spindle 27 is a follower D. The follower D is preferably formed from pressed metal for lightness and economy of manufacture. The follower D is provided with a central hub 31 and a plurality of indentations 32 and 33 formed to extend above the margin 34 of the plate. Immediately within the margin 34, the plate is offset to provide an elevated surface 35 and a circumferential rib 50. The follower D is rotatably supported on the spindle 27 by applying the hub 31 of the follower to the reduced end 29 of the spindle, whereupon the extremity of the reduced portion 29 is peened or otherwise fashioned to connect the follower D to the spindle 70 in irremovable relationship, but at the same time, to allow relative rotation between them.

In the formation of the follower D, the indentations 32 are segmental indentations, circumferentially spaced and formed inwardly of the 75 margin of the rib 54 of the plate, so that be-

tween the outer boundaries of the segmental indentations 32, substantially flat surfaces 36 are formed. The indentation 33 is fashioned in the form of a modified Greek cross, with the outer extremities of the arms of the cross substantially arcuate, as at 37.

By constructing the follower D in the manner described, there are provided four guideways of different diameters for thus receiving and centering cans having correspondingly different diameters. For example, the largest can, a No. 3, is guided by means of the application of the flange of its closed end over the margin 34 of the plate and bearing against the rib 54. The next largest can, a No. 2 1/2, is centered on the follower 15 plate by applying the flange of its closed end against the outside margins of the segmental indentations 32. The next smaller can, a No. 2, is centered and guided by the follower by applying the flange of the closed end of the can 20 against the inside margins of the segmental indentations 32, while the smallest can, a No. 1, which may be centered on the follower D as herein illustrated, is applied to the plate with the flange of its closed end against the arcuate extremities 37 of the arms 36 of the indentation 33.

The follower plate D is provided with a plurality of holes 38, 39, 40 and 40a, arranged in groups, and with the holes of a group formed at different distances from the center of the plate, 30 for a purpose to be later explained.

Telescopically movable within the polygonal bore 28 of the spindle 27 is a correspondingly shaped polygonal tail pin 41 having formed in it, near its upper end, a plurality of holes 42, 42a 35 and 42b at different points in the length of the tail pin to be placed in register with one of the bores 29 of the spindle for receiving the connecting pin 30 to connect the tail pin 41 and spindle 27 in adjusted telescopic arrangement for disposing 40 the follower plate D at a desired height to conform to the height of a can to be sealed or opened, as the case may be.

The bores 29, 29a, 29b, 29c and 29d are axially spaced, one from another, a distance commensurate with the length of a can body as cut off by successive opening operations. That is to say, the distance between the bores 29 and 29a corresponds to the amount a can is shortened when it is cut open the first time. The distance between the bores 29a and 29b corresponds to the amount a can is shortened by the second opening, and the other bores correspond to subsequent openings, so that uniform heights of cans for the successive cuttings or openings is maintained.

55 Formed below the part 24 of the frame member are ears 42 which are in spaced relationship and are formed as an integral part of the boss 1 which carries the thumb bolt 2. A bar 43 passes through registering apertures in the ears, and between the ears a cam disc 44 is secured to the bar by means of a pin 45. The pin enters a suitable opening in the cam disc and engages a notch in the bar 43 to connect the cam disc to the bar in fixed relationship. After the pin 45 has been inserted in the opening in the disc the outer end margin of the opening is peened to secure the pin 45 in position. The bar has a bent portion 46 which serves as a handle for manipulating the cam disc 44. The parts are so arranged that 70 the lower end of the tail pin 41 always rests on the cam disc 44. The disc 44 has a flat portion 44a.

Pivoted to the upper part 6 of the frame A, by means of a bolt 47, is an oscillating arm 48. 75

Carried by the arm, on one side of the pivot 47 is a seaming roller M, which is retained in operative position by means of a bolt 49 passing through the center of the roller and engaging a threaded aperture in the arm. Supported on the arm at a point on the other side of the pivot 47, is a second seaming roller N which, in like manner, is removably attached to the arm by means of a bolt 50. The bar 48 is provided with a handle portion 51 for swinging it. As will be observed, the bar 48 is adapted to swing in a horizontal plane.

Nowadays, a housewife may purchase new cans which are closed at one end and open at the other end, new covers and gaskets, and may, herself, with an apparatus of the present invention, can foods and the like. Such cans are available in a plurality of sizes with covers of corresponding sizes. The open ends of such new cans are flared or flanged.

Suppose a housewife has purchased some No. 3 cans for home canning. A can, after being properly sterilized and filled is then put on the follower D, with the flange of its closed end fitting about the rib 54, thus centering the can. A cover F with the gasket 53 in it is then placed over the open end of the can and the handle 46 operated to rotate the cam disc 44 against the tail pin 41 to elevate the follower, can and cover against the chuck C. Such elevating movement causes the chuck to enter the depression in the cover F. By this time, the flat portion 44a of the disc 44 is against the tail pin 41, thereby locking the parts against retrograde movement.

The handle 9 is rotated while the lever 48 is swung to force the first seaming roller N against the cover flange, and the cover flange partially rolled under the flared margin of the can. The gasket 53 is also curved by this operation, all as may be observed in Figure 9. After a few rotations against the seaming roller N, the lever is swung to force the second seaming roller M against the cover flange, and the sealing operation is completed, in hermetically sealed relation, as may be seen in Figure 10.

To prevent too great movement of the seaming rollers against the can seam, the rollers M and N are constructed with overhanging parts 62 and 63, respectively. These parts contact a vertical shoulder 64 formed in the chuck C and thus limit the inward movement of the rollers.

After the lot of No. 3 cans has been sealed, they are suitably sterilized and put away for later use.

When a can is to be opened, the roller N is removed from the lever 48 and a cutting roller P substituted, the filled can is inserted in the machine, rotated, and the cutting roller P moved against the can so that its cutting edge 56 cuts the can body just underneath the can seam, as may be seen in Figure 11.

The bores 29, 29a, etc., in the spindle 27 are axially spaced to conform to the amount of can severed by the opening operation, i. e., the distance between the top of the can flange and the cutting edge 56 of the cutting roller P.

When using a new No. 3 can, the tail pin 41 is moved in the spindle 27 until the hole 42 of the pin is in register with the uppermost bore 29, whereupon the pin 30 is inserted therein. To seal a new top to a No. 3 can, after the first opening, the hole 42 of the tail pin 41 is brought into register with the bore 29a of the spindle 27, thus raising the spindle the proper distance. For the second cutting of the same can, the hole 42 of the tail pin 41 is moved to register with the

bore 29b of the spindle, and the other adjustments made for other cutting of No. 3 cans.

The hole 42a of the tail pin 41 is used with No. 2 and No. 2½ cans in a similar manner, while the hole 42b is used for No. 1 cans, and the several adjustments for such other cans are made as heretofore described.

Of course, prior to the application of the can to the follower, it has been filled with its contents and a lid or cover, designated generally at 10 F, is applied over the flared extremity 52 of the can, whereupon the handle 46 is actuated to cause the cam disc 44 to raise the follower D to effect driving relationship between the chuck C and the recess or depression within the cover F 15 as applied to the can.

Any can of a different diameter would be sealed in the same manner, with a cover of corresponding diameter. In such event, a chuck C of proper diameter would be utilized and readily applied to the driving spindle 8, simply by pulling off the first chuck and applying the necessary chuck to the spindle, in the manner heretofore described, and the proper adjustment of the tail pin 41 and spindle 27 made.

The cutting roller P is formed with an annular face 55 of sufficient height to receive in it the seam of the can, and has a cutting edge 56 which is formed to a shearing angle. The cutting roller P is so constructed that the body of the can is sheared immediately below the lower margin of the can flange, to eliminate as little as possible of the can body, and thus afford a can of slightly less size for reuse. After the can has been emptied, it is suitably cleaned and sterilized to be later used for canning purposes. When the shortened can is to be reused, the flare 52 is formed thereon in the manner heretofore described and the sealing process carried out, utilizing, of course, a new cover and sealing gasket 40 53.

The active faces of the rollers M and N for seaming a cover to a can are such as to secure the proper sealing of the cover with a slight movement of the handle 48. With the construction herein described, considerable pressure is applied to compress the can cover seam and thus effectively seal a cover to a can. The strong end pressure effected in clamping a cover to the driver plate C and the upward pressure exerted by the follower D tends to force the initially outwardly flared upper margin of the can into the curl of the seam fold.

It will be observed that the apparatus of the present invention provides an exceedingly simple, inexpensive and efficient double-seaming apparatus which is manually operable and thus adapted to the requirements of housewives who do their own canning, or of such canners who put up only small quantities of goods at a time. The apparatus of the present invention also efficiently hermetically seals cans without the use of solder or other binding agents, the sealing being accomplished solely by mechanical means.

Referring to Figure 6 of the drawings, it will be observed that the telescopically arranged spindle 27 and tail pin 41 may be adjusted to accommodate the height of the follower D to any length of normal can in use, or which would be used by a housewife. As the cans are shortened by successive opening operations, the spindle 27 may be moved upwardly on the tail pin 41 by knocking out the driving pin 30, by means of the end 67 of the pin R, and then relatively adjusting the tail pin 41 and spindle 27 to approximate the de-

sired height of the follower. When such relationship has been established, the pin 30 is inserted in the proper one of the bores 29 and hole 42 to thus connect the telescoping parts together in axially adjusted relation.

By providing the polygonal bore 28 in the spindle 27 and the polygonal tail pin 41, all rotative stress is removed from the pin 30, so that it is not necessary that the pin be strong enough to afford driving relation between the telescopic parts.

By making the part 24 of the frame extending downwardly from the bottom 5, the whole apparatus may be positioned lower on the support 15 B than would be possible if the part 24 and the rod 43 were all above the lowermost plane of the apparatus base. The undersurface of the overhanging part 6 of the frame A adjacent the pivot of the swinging lever 48 is provided with an enlarged flat surface 71 to form a flat bearing face 20 for the lever and thus prevent any tilting movement of the lever during sealing, flanging or cutting, thus assuring an open-ended can with all points in the edge thereof in the same plane, and 25 thereby assuring sufficient material adjacent said end to afford an even flare or flange for resealing purposes.

The invention has been described herein more or less precisely as to details, but it is to be understood that the invention is not to be limited thereby, as changes may be made in the arrangement and proportion of parts, and equivalents substituted without departing from the spirit and scope of the invention.

35. The invention is claimed as follows:

1. A hand-operated double-seaming apparatus for cans which comprises the combination with a suitable frame having provision for securing it to a support such as a table or ledge, a rotatable driver or chuck supported in said frame and 40 adapted to enter and fit the recess in a can cover, a follower axially aligned with said driver and adapted to be moved toward and away from said driver, a handle for rotating said driver and a can supported between it and the follower, said 45 follower comprising a plate rotatively mounted on a spindle, said spindle having a bore to receive a tail pin, a tail pin centered in said spindle bore, means for adjustably connecting said spindle and tail pin to adjust the position of the follower with respect to the driver to accommodate cans of different heights, cam means acting 50 directly against said tail pin for moving said follower and a supported can into driving relation with said driver, a single oscillatable lever pivoted between its ends to said frame adjacent the driver, a roller rotatably mounted on said lever near one end thereof and another roller rotatably mounted on said lever between its pivot and the other end of the lever, the rollers being movable 55 successively in arcuate paths about the lever pivot as a center and against the can cover for sealing the cover to the can.

2. In a can sealing machine, a rotatable can-holding driver or chuck having a driving head 60 which is adapted to fit the recess of a can cover, a swinging lever pivoted between its ends, a roller rotatably mounted on said lever near one end and another roller rotatably mounted on said lever between the lever pivot and its other end, said rollers adapted to be successively applied 65 against the cover flange to seal the cover to the can and movable through arcuate paths the centers of which are the lever pivot, a cooperating follower adapted to hold a can and its cover in 70

driving relation with said driver, and said follower being provided with means for centering cans of different diameters on it.

3. In a hand-operated can top sealing apparatus of the class wherein cans of different sizes 5 are presented for sealing and wherein a can support or lifter plate is utilized for holding a can against a chuck; the combination of means for vertically adjusting said can support or lifter plate without the use of separate fillers, shims 10 and the like; said means including a hollow spindle on which said can support or lifter plate is freely rotatable and on which it is permanently carried; the hollow interior of said spindle being polygonal in section; a polygonal tail pin 15 slidably fitted in said hollow spindle to prevent relative rotative movement between said spindle and tail pin; and a pin passed through registering openings in said spindle and tail pin to lock them together in desired longitudinal adjustment. 20

4. In a hand-operated can top sealing apparatus of the class wherein cans of different sizes are presented for sealing and wherein chucks of different sizes are used for sealing cans of different diameters, the combination of means for 25 removably connecting a chuck to its driving shaft, said means including a shaft having an end provided with a portion adapted to receive a driving chuck, said shaft end and driving chuck having cooperating means to prevent relative rotation between them, and yieldable means for holding a chuck on the end of said shaft whereby said chuck may be removed from said shaft by pulling action.

5. In a hand-operated can top sealing apparatus of the class wherein cans of different sizes are presented for sealing and wherein chucks of different diameters are used for sealing cans of different diameters, the combination of means for 35 removably connecting a chuck to its driving shaft, said means including a shaft having a flattened portion adapted to receive a driving chuck, a driving chuck having a straight portion for contacting the flattened portion of said shaft to prevent relative rotation between them, and yieldable 40 means for holding a chuck on the end of said shaft whereby said chuck may be removed from said shaft by pulling action.

6. In a hand-operated can top sealing apparatus of the class wherein cans of different sizes 50 are presented for sealing and wherein a can support or lifter plate is utilized for holding a can against a chuck; the combination of means for vertically adjusting said can support or lifter plate without the use of separate fillers, shims 55 and the like; said means including a hollow spindle on which said can support or lifter plate is freely rotatable and on which it is permanently carried; the hollow interior of said spindle being polygonal in section; a polygonal tail pin 60 slidably fitted in said hollow spindle to prevent relative rotative movement between said spindle and tail pin; a pin passed through registering openings in said spindle and tail pin to lock them together in desired longitudinal adjustment, and 65 cam means directly contacting the tail pin and operable to elevate the can support or lifter plate to can holding position.

7. In a hand-operated can top sealing apparatus of the class wherein cans of different sizes 70 are presented for sealing and wherein a can support or lifter plate is utilized for holding a can against a chuck; the combination of means for vertically adjusting said can support or lifter plate without the use of separate fillers, shims 75

and the like; said means including telescoping spindle and tail pin contoured to prevent relative rotative movement between them; means for connecting said spindle and tail pin together in longitudinally adjusted position, said can support or lifter plate being permanently carried by

said spindle and being freely rotatable on the spindle; and elevating means acting directly against said tail pin to raise the can support to can holding position.

JOHN JUNKUNC. 5
